Patented Nov. 19, 1918.

FIG. 1.

FIG. 2.

FIG. 3.

Inventor
Alexander Horwitz,
By his Attorneys

Edgar Clark & Co.

UNITED STATES PATENT OFFICE.

ALEXANDER HORWITZ, OF NEW YORK, N. Y.

SOAP CONTAINER AND DELIVERER.

1,285,186.

Specification of Letters Patent. Patented Nov. 19, 1918.

Application filed February 2, 1918. Serial No. 215,139.

To all whom it may concern:

Be it known that I, ALEXANDER HORWITZ, a citizen of the United States, and residing at New York, in the county of New York and State of New York, have invented certain new and useful Improvements in Soap Containers and Deliverers, of which the following is a specification, such as will enable those skilled in the art to which it appertains to make and use the same.

This invention relates to devices designed to serve as soap containers and deliverers and particularly to devices of this class designed for use in garages and similar places where automobiles and other vehicles are stored or stabled, and where large amounts of soap are used in washing or cleaning such vehicles; and the object of the invention is to provide an improved device of the class specified which may be manipulated so as to deliver any desired amount of soap in condition for use; and whenever necessary, and by means of which the soap will be kept clean at all times and in proper condition for use; a further object being to provide a device of the class specified which, in addition to serving as a container and deliverer of soap, may also be made to serve as a container and deliverer for other plastic substances such as grease or heavy oils; and with these and other objects in view the invention consists in a device of the class specified, constructed and operated as hereinafter described and claimed.

The invention described and claimed herein is an improvement on that described and claimed in a prior patent granted to me March 19, 1918, No. 1,259,741, and is fully disclosed in the following specification, of which the accompanying drawing forms a part, in which the separate parts of my improvement are designated by suitable reference characters in each of the views, and in which:

Figure 1 is a side and sectional view of my improved soap container and deliverer;

Fig. 2 a section on the line 2—2 of Fig. 1 with the parts in a different position; and,

Fig. 3 is a partial transverse section on the line 3—3 of Fig. 2.

In the practice of my invention, I provide a frame or casing *a* which, in the construction shown, is tubular in form and to the lower end of which is connected a bottom *a*² having an annular rim portion *a*³, and detachably connected with the bottom *a*² cen-

trally thereof is a threaded shaft *b* which passes through the frame of casing *a* and protrudes beyond the open end portion *a*⁴ thereof, as shown at *b*², and is provided with a detachable cap *b*³. The end portion *b*⁴ of the shaft *b* is reduced and threaded, and a lock nut *b*⁵ is employed for locking said shaft in connection with the bottom *a*², as clearly indicated in Figs. 1 and 2 of the drawing.

Rotatably mounted on the shaft *b* is a soap container and deliverer *c* which is cylindrical in form and provided with a bottom *c*² having an enlarged central threaded portion *c*³ through which the shaft *b* is adapted to pass. The container *c* is open at its other end and provided with a detachable cap *d* with which is detachably connected a hopper *e*, having a neck portion *e*² provided with a plurality of apertures *e*³ through which the material of the container *c* is adapted to pass as hereinafter described.

The hopper *e* is provided adjacent to the neck portion *e*² thereof with a discharge port or passage *e*⁴ controlled by the valve *e*⁵ pivoted at *e*⁶, and provided with a handle or finger piece *e*⁷ by which it may be manipulated.

Mounted on the shaft *b*, within the container *c*, is a supplemental bottom *f*, the central portion of which is threaded as shown at *f*² to correspond with the threads on the shaft *b*, and the lower face of said bottom *f* is recessed as shown at *f*³, and pivotally mounted on the supplemental bottom *f* within the recess *f*³ are pawls *g*, two of which are employed, said pawls being adapted to operate in connection with oppositely arranged recesses *b*⁶ in the shaft *b* adjacent to the end portion *b*² thereof as clearly indicated in Figs. 2 and 3 of the drawing. The pawls *g* are normally held in engagement with the shaft *b* by suitable springs *g*², as clearly indicated in Fig. 3, and with this construction when the supplemental bottom *f* is in the position shown in Figs. 2 and 3, said bottom is held against rotation on said shaft, or said shaft through said bottom in one direction.

The supplemental bottom *f* is preferably provided in the periphery thereof with a packing ring *h* of any kind or class for the purpose of preventing the passage of soap or other substances in the container around the supplemental bottom in the operation of the device, as hereinafter de-

scribed. The function of the cap b^s is to prevent the supplemental bottom f from displacement from the shaft b in the operation of the device, but by detaching said cap, 5 said bottom may be detached from the shaft b for cleaning or other purposes.

From the foregoing description the operation of my improved device will be readily understood when taken in connection 10 with the accompanying drawing and the following statement. The position of the parts shown in Fig. 1 might be regarded as the normal position thereof, or the position 15 the parts will assume when my improved soap container and deliverer is shipped from place to place, and if the container in the position shown in Fig. 1 is or has been filled with soap, the operation 20 of discharging the soap therefrom will be as follows. The container c is rotated on the shaft b to bring said container into the position shown in Fig. 2, which operation is accomplished by grasping the hand-piece 25 d^2 connected with the container c , or the cap portion d thereof, and in the above operation of raising the container c on the shaft b , the supplemental bottom f will also be raised into the position shown in Fig. 2, as will be readily understood. When it is 30 desired to discharge a portion of the contents of the container c , said container is rotated on the shaft b in the opposite direction, or to cause said container to descend on said shaft, in which operation the supplemental bottom f is held against rotation 35 by reason of the engagement of the pawls g with the recesses b^s in the shaft b , and by reason of this fact the contents of the container is forced out through the apertures 40 e^s in the neck portion e^2 of the hopper e , and may be removed from said hopper in the usual or any desired manner.

It will be understood that the continuation 45 of the above operation of rotating the container c on the shaft b to move said container into the position shown in Fig. 1 will discharge all of the contents of the container through the apertures e^s , and at the end of this operation, the supplemental 50 bottom f will be in the position shown in Fig. 2, with the container c in the position shown in Fig. 1, and when it is desired to refill the container or to clean the same, or the separate parts thereof, the cap d is removed, the cap b^s detached from the shaft b , and said shaft detached from the bottom a^2 of the frame or casing a , and the bottom c^2 of the container c , after which the supplemental bottom f may be detached therefrom. 55 In reassembling the parts, the supplemental bottom f is first connected with the lower end portion of the shaft b , after which said end portion of the shaft is connected with the bottom c^2 of the container c 60 by passing said shaft with the supplemental 65

bottom thereon downwardly through the container c , and then securing said end portion of the shaft b to the bottom a^2 of the frame or casing a , which brings the parts in the position shown in Fig. 1, as will be 70 readily understood.

While I have described one method of discharging the contents of the container c , it will be understood that the container may be shipped to the user or purchaser in 75 the position of the parts shown in Fig. 1 without any soap or other substance therein, and when it is desired to use said container or to fill the same with the desired substance, the container c may be first raised 80 into the position shown in Fig. 2, after which said container may be filled by detaching the cap d , or the hopper e , and in this way a greater amount of the substance 85 employed may be introduced, but the operation of discharging the substance in the container c will be exactly the same as that described in connection with the first-named use of the device.

While I have shown a construction for 90 accomplishing the desired result, it will be understood that my invention is not limited to the details thereof, as herein shown and described, and changes therein and modifications thereof may be made, within the 95 scope of the appended claims, without departing from the spirit of my invention or sacrificing its advantages.

Having fully described my invention, what I claim as new and desire to secure by 100 Letters Patent, is:—

1. In a device of the class described, a cylindrical frame or casing open at one end and closed at the other, a threaded shaft detachably connected with the closed end of 105 said frame or casing and passing axially therethrough, a container mounted in said frame or casing and adapted to rotate on said shaft, a supplemental bottom mounted in said container and rotatably mounted on 110 said shaft, and devices connected with said supplemental bottom adapted to engage cut-out portions on one end portion of said shaft to lock said supplemental bottom against rotation thereon in one direction. 115

2. In a device of the class described, a cylindrical frame or casing open at one end and closed at the other, a threaded shaft detachably connected with the closed end of 120 said frame or casing and passing axially therethrough, a container mounted in said frame or casing and adapted to rotate on said shaft, a supplemental bottom mounted in said container and rotatably mounted on said shaft, devices connected with said supplemental bottom adapted to engage cut-out portions on one end portion of said shaft to lock said supplemental bottom against rotation thereon in one direction, and means 125 detachably connected with said end portion 1

of the shaft for preventing the detachment of said supplemental bottom from said shaft.

3. In a device of the class described, a frame or casing, a shaft mounted therein, a container rotatably mounted on said shaft, a supplemental bottom rotatably mounted on said shaft and movable through said container, and means on said supplemental bottom adapted to operate in connection with a cut-out portion on one end of said shaft for locking said supplemental bottom against rotation on said shaft in one direction.

4. In a device of the class described, a cylindrical casing open at one end and provided with a central threaded shaft, a container rotatably mounted on said shaft and movable through said casing, a supplemental bottom rotatably mounted on said shaft and adapted to move through said container, and means on said supplemental bottom adapted to operate in connection with a cut-out portion on one end of said shaft for locking said supplemental bottom against rotation on said shaft in one direction.

5. In a device of the class described, a frame or casing, a shaft mounted therein, a container rotatably mounted on said shaft, said container being provided with a detachable cap, a hopper detachably connected with said cap, a supplemental bottom rotatably mounted on said shaft and movable through said container, means for prevent-

ing the detachment of said supplemental bottom from said shaft in its movement thereon, and means on said supplemental bottom adapted to operate in connection with a cut-out portion on one end of said shaft for locking said supplemental bottom against rotation on said shaft in one direction.

6. In a device of the class described, a cylindrical frame or casing one end of said casing being closed and the other open, a shaft mounted centrally of the closed end portion of said frame or casing and passing axially therethrough, a container rotatably mounted on said shaft and movable through said casing from the closed end portion to the open end portion thereof, a supplemental bottom mounted in said container and rotatably mounted on said shaft, and means on said supplemental bottom adapted to operate in connection with a cut-out portion on one end of said shaft for locking said supplemental bottom against rotation on said shaft in one direction.

In testimony that I claim the foregoing as my invention I have signed my name in presence of the subscribing witnesses this 20th day of January, 1918.

ALEXANDER HORWITZ.
